2,388,275

TUYÈRE CONSTRUCTION

Dorothy E. Mackenzie and George H. Wolfe,
Reno, Nev.

Application December 24, 1943, Serial No. 515,552

2 Claims.

(Cl. 266—41)

The invention relates to a tuyère construction of the kind adaptable for use in regulating the amount of air admitted to the fire zone of a gas producer apparatus.

The tuyère construction of the invention has been found particularly useful in connection with a gas producer apparatus of the type which is shown in Letters Patent No. 2,278,798, issued April 7, 1942, to A. Riccardi, and which apparatus is used to generate and supply a combustible gas to the internal combustion engine of an automotive vehicle. In such an apparatus, the tuyère which is ordinarily used is cast in one piece from a nickel chrome alloy which is resistant to destruction at high temperatures and is installed on the apparatus so that the tip portion thereof projects into the fire zone of the apparatus. The high temperature present in this fire zone, which usually reaches a temperature as high as 2750° F., effects a rapid oxidation of the tip portion of the tuyère and in due time the length of said tip portion becomes so short that the entire tuyère becomes useless and has to be discarded and an entire new tuyère substituted.

It is the main object of the present invention to improve upon the construction of tuyères used in such an apparatus as well as upon the construction of tuyères generally, and to provide a tuyère in which the tip portion thereof is made so that it is removable from the body portion of the tuyère and so that when the tip becomes unusable due to the action of the heat it is subjected to in the fire zone of the apparatus, it can be removed from the body portion and a new tip installed without the necessity of discarding the entire tuyère.

Another object of the invention is to provide a tuyère construction wherein the body portion thereof which is not subjected to the heat of the fire zone of the gas producer apparatus is made of a comparatively inexpensive metal and the removable tip portion which projects into the fire zone is made of a material which is especially adapted to resist high heat temperatures.

A further object is to provide a tuyère construction made up of a body portion which is made of an inexpensive metal such as semi-steel, and of a removable tip portion which is made of a refractory material which is resistant to high heat temperatures.

A further object is to provide a tuyère construction made up of three separable sections comprising a body portion made of a semi-steel or of an equivalent inexpensive metal, a tip portion made of a refractory material which is re-

sistant to high heat temperatures, and a collar made of a steel tubing and which functions to hold the body portion and the tip portion in assembled relation with respect to each other.

5 Further objects will appear more fully hereinafter.

The attached drawing illustrates the tuyère construction made in accordance with the invention, and in which

Figure 1 is a sectional view in elevation of the tuyère construction with the several parts thereof shown in their assembled condition;

Figure 2 is an elevational view partly in section, of the body portion of the tuyère construction;

Figure 3 is an elevational view, partly in section, of the tip portion of the construction; and

Figure 4 is an elevational view, partly in section, of the retaining collar used in the construction.

Referring more particularly to the drawing it will be seen from the several views thereof that the tuyère construction is composed of three separate elements, namely, a body portion indicated generally by the letter A; a tip portion, indicated by the letter B; and a retaining collar designated by the letter C. These three elements when assembled together as shown in Figure 1, comprise a somewhat conical shaped tuyère or nozzle having a central opening therethrough which is indicated at D.

The body portion A, comprises a hollow cylindrical body and is intended to be made of a semi-steel metal or of any other suitable inexpensive metal. The lower end of the conical shaped opening extending through the body portion is of a diameter which will coincide with and register with the diameter of the opening which is formed through the tip portion B when the said tip is in assembled relation with respect to the body portion. The body portion has its upper free end formed with a flanged portion 1 which is adapted to be connected in any suitable manner to an air supply source. The exterior circumference of the body portion is formed with a reduced portion 2 which terminates at its lower end in a horizontally extending bottom 3, which at its inner end has a downwardly extending inclined face 4. The body portion also is provided with a screw threaded opening therein which is adapted to receive the collar retaining screw 5 therein, as will be more fully referred to hereinafter.

The tip portion B, of the construction, is intended to be made of a suitable refractory material which is resistant to destruction by heat such

for instance as silicon carbide. However, the tip may also be made of a suitable alloy having similar properties. The tip is desirably made in a slightly tapering cylindrical shape with a central opening extending therethrough and is also formed with an enlarged head portion having a horizontally extending top face 6 which at its inner end is provided with a downwardly inclined portion 7. The horizontally extending face 6 and the inclined portion 7 are adapted to coincide with and abut against the horizontally extending bottom face portion 3 and inclined face 4 of the lower end of the body portion A when said body portion and tip portion are in assembled relation with respect to each other. The exterior circumference of the enlarged head of the tip is formed with an inclined portion 8 which extends between the head and the main body portion thereof indicated at 9.

The retaining collar C of the tuyère construction is made of steel tubing and has its interior circumference formed with an inclined face 10. The collar is also provided with a screw threaded opening therethrough indicated at 11 in Figure 1 and which opening coincides with the opening formed in the body portion A when the collar is in assembled relation with said body portion and the tip portion and said collar is held in position with respect to said body portion and tip portion by means of the screw 5.

When the collar is in respect to the body portion and the tip as shown in Figure 1, it surrounds the lower end of the body portion and the head of the tip, and its interior surface abuts against the surfaces 2, 8^a, and 8, of the body portion and the tip, and when it is screwed in place by the screw 5, it clamps the body portion and tip portion securely together.

It will be seen from the above description and by reference to the drawing that we have provided a tuyère construction which has several advantages. In the first place, it is comprised of three independent and separable parts which can be disassembled so that if the tip portion needs to

be replaced it can be readily taken from the assembly and a new tip substituted therefor. Secondly, by making the body portion and collar of a cheaper metal the cost of manufacture of the tuyère is greatly decreased. Also, by providing a removable tip to the tuyère construction it is possible to use tips made of different heat resisting materials and especially tips made of refractory materials which do not wear out or oxidize as easily as tips made of other heat resisting materials. In addition to the above advantages, the operator of a gas producer apparatus when utilizing such a tuyère construction can keep on hand an extra supply of tips for use and can substitute the same in the tuyère without having to install an entirely complete tuyère when a tip becomes worn out.

While we have described the tuyère construction of our invention as adaptable for use in a gas producer apparatus of the type shown in the aforesaid Letters Patent No. 2,278,798 it is obvious that it may be used in connection with any apparatus where air is introduced into a fire combustion zone. We therefore do not desire to be restricted to the use of the tuyère construction in connection with any particular type of gas producer apparatus.

What is claimed is:

1. A tuyère construction comprising a body portion made of a semi-steel, and a removable tip portion made of material resistant to destruction by heat, and a metallic collar secured around the body portion and the tip portion for holding said tip portion in position with respect to the body portion.

2. A tuyère construction comprising a body portion made of a metallic material, and a separable tip portion made of an alloy resistant to destruction by high temperature, and a metallic collar means surrounding the outer end of the body portion and the inner end of the tip portion to hold said tip portion to the body portion.
